UNITED STATES PATENT OFFICE

GEORGE S. STEVENS, OF BOSTON, MASSACHUSETTS

SKI

Application filed August 10, 1931. Serial No. 556,213.

- This invention relates to novel improvements in skis. With the prevailing types now in use the toe clips are attached directly to the skis by means of large wood screws. 5 In order to avoid splitting the wood of which the ski is made, it is necessary to drill the wood with two different sizes of drills in order properly to fasten the screws. Users of skis do not generally possess proper tools 10 nor skill for doing this work. Furthermore, in case of any adjustment to be made, these screws must be loosened, and in a short space of time will not hold tight. In addition to these points the distance between the screws 15 is fixed and thus does not permit variation of any extent in the angle between the vertical part of the toe clip and the edge of the ski. Further, where the attachment of the toe plate to the ski is localized at the toe 20 there is considerable tendency to breakage. It is an object of my invention to improve the connection between the toe clip and the ski by extending the metal foot plate a sufficient length to extend beneath the entire sole and 25 heel of the boot thereby preventing the accumulation of snow on top of the ski under the boot.
- It is also an object of my invention to have the metal foot plate rigidly and permanently attached to the ski over an extended 30 distance to thus avoid danger of splitting the ski or localizing the connection to the areas immediately beneath the toe.
- A further object of my invention is to 35 provide an improved and flexible adjustment of the toe clips relatively to the foot plate without loosening the attachment between the foot plate and the ski.
- Other objects of my invention will be apparent from the following description of the preferred form as illustrated in the accompanying drawings in which;
- Fig. 1 is a plan view of my novel foot plate; 40 Fig. 2 is a plan view of the same showing the toe clips in adjusted position;
- Fig. 3 is a vertical longitudinal section on the lines 3—3 of Fig. 2 and
- Fig. 4 is a fragmentary side elevation thereof.
- 50 By way of example I have shown my in-
- vention to be applied to a wooden ski 5. The metal foot plate 6 is long enough to extend beneath the entire foot of the boot. This plate 6 has reinforcing ribs 7 around its periphery and transversely of the plate. A series of counter-sunken wood screws 8 are attached as indicated to the foot plate and run into the top surface of the ski 5. As is indicated in Fig. 1 the upper surface of the front of the foot plate is knurled or otherwise roughened to form an adequate frictional contact with the toe clips. 55
- This roughened area carries two round holes 9, 9 by which the toe clip attaching means is held.
- Behind the holes 9, 9 is a second pair of holes 10, 10. The latter holes are elongated longitudinally of the foot plate 6. 60
- As shown clearly in Fig. 3 a series of bushings 11, 11 are held within the holes 9 and 10. These bushings have extended irregular bottom flanges and a central screw threaded opening. Each flange is cut away along one side so as to be held against turning by the adjacent longitudinal stiffening rib. The bushings in the holes 9 are fixed 70 in position while those in the holes 10 may move longitudinally during the adjustment of the toe clips.
- The toe clips or plates 12, 12 are comprised 75 of a base 13 and side portions 14. The side portions 14 have strap openings 15 and in the rear have ears 16.
- A strap fitting 17 attached to strap 18 is held in ear 16 by means of fastenings 19. 80
- The base 13 of toe plate 12 has a pair of transversely elongated holes 20, 20. These holes have depressed flanges 21 upon which rest the flat head bolts 22 flush with the top surface of the plate 13. 85
- The bolts 22 are threaded into the bushings 11 by means of screw threaded shanks 23.
- 90
- From the above description it will be readily understood that I have provided a foot plate 6 with even distribution of the attachment to the ski 5 by means of the numerous screws 8. At the same time by reason of the reinforcement 7 a space is provided in which the bushings 11 may freely turn or slide to facilitate adjustment of the toe clips.
- 95
- 100

The toe clips are roughened on their lower surfaces to engage in a positive manner on the upper knurled surface of the plate 6 and thus retain any adjusted position given them.

5 By means of the flat head bolts 22 holding in the bushings 11 the toe plates may be firmly fastened to the plate 6. Suitable adjustment both as to width of the toe plates and inclination of the vertical sides 14 is permitted by having the laterally extended openings 20 in the toe plates and the coaxing longitudinally extending openings 10 in the foot.

It will be readily seen how the toe plates 15 may be given any desired adjustment and securely fastened. Also the attachment of the wooden ski is securely accomplished without danger of the screws working loose or the wood splitting.

20 While the preferred form of my invention has been described and illustrated I desire it to be understood that no limitation is implied other than what is consistent with the scope of the appended claims.

25 What I claim is:

1. In combination with a ski, an extended foot plate attached thereto, said foot plate having a frictional surface, toe clips having frictional lower surfaces, and means for fastening the toe clips with their frictional surfaces in extended co-acting engagement with the frictional surface of the foot plate.

2. In combination with a ski, an extended foot plate attached thereto, said foot plate having a frictional surface, toe clips having frictional lower surfaces, and means for fastening the toe clips in variable angular relationship with their frictional surfaces in extended co-acting engagement with the frictional surfaces of the foot plate.

3. In combination with a ski, an extended foot plate attached thereto, toe clips, pivotal fastenings between the forward portions of the toe clips and the foot plate, and laterally 15 slidable fastenings between the clips and plate in rear of said first named fastenings.

4. In combination with a ski, an extended foot plate attached thereto, flanged bushings wholly above the top surface of the ski and 50 extending upwardly through the foot plate, toe clips mounted on the upper surface of the foot plate, and fastening means on said clips attached to said bushings.

5. In combination with a ski, an extended foot plate attached thereto, a flanged bushing held by the foot plate, a second flanged bushing slidably held by the foot plate, a toe clip and means on said clip for fastening it to each of said bushings.

30 In testimony whereof I have affixed my signature.

GEORGE S. STEVENS.
